UNITED STATES PATENT OFFICE.

CHARLES L. LEONARD AND ALLEN F. HOWARD, OF IONIA, MICHIGAN.

BEET-TOPPING MEANS.

1,353,403.

Specification of Letters Patent. Patented Sept. 21, 1920.

Application filed December 17, 1918. Serial No. 267,198.

To all whom it may concern:

Be it known that we, CHARLES L. LEONARD and ALLEN F. HOWARD, citizens of the United States, residing at Ionia, in the 5 county of Ionia and State of Michigan, have invented certain new and useful Improvements in Beet-Topping Means; and we do hereby declare the following to be a full, clear, and exact description of the invention, 10 such as will enable others skilled in the art to which it appertains to make and use the same.

This invention relates to beet topping means, and more particularly to a means of 15 the character stated specially adapted to be used as an attachment for a beet harvesting machine.

One of the main objects of the invention is to provide a topping mechanism of simple construction and operation which may 20 be readily applied to a beet harvester of standard construction.

A further object is to provide an attachment including means for severing the tops 25 from the beets, this attachment being further provided with guiding and elevating means adapted to bend the leaves of the beets over and to bring the cutting members 30 into engagement with the top portion of the beets when the leaves are thus bent so as to sever the tops therefrom.

A further object is to provide hingedly mounted supporting plates which carry 35 guide plates and cutting means, the guide plates being adapted to engage the beets during forward movement of the machine so as to bend the leaves thereof over and bring the cutting means into operative engagement with the beet tops.

40 Further objects will appear from the detailed description.

In the drawings:

Figure 1 is a side view of a topping mechanism constructed in accordance with our 45 invention as applied to a beet harvester of conventional construction.

Fig. 2 is a top plan view of the attachment.

Fig. 3 is an enlarged side view.

50 Fig. 4 is an underneath plan view.

Fig. 5 is a section taken substantially on line 5—5 of Fig. 4.

Fig. 6 is a detail side view of one of the 55 guide plates and cutter head and associated parts.

Fig. 7 is a detail side view of one of the guide plates.

Fig. 8 is a section taken substantially on line 8—8 of Fig. 4.

Fig. 9 is a section taken substantially on 60 line 9—9 of Fig. 2.

Our attachment may be used in connection with a beet harvester of any suitable or preferred construction such as that illustrated embodying the frame designated generally by A, this frame being provided adjacent its forward end with spaced uprights 2 which support a horizontal bar 3 extending transversely of the frame. The uprights 2 are connected to similar uprights 4 positioned in rear thereof by horizontal side bars 5 of the frame. As stated, this frame may be of any suitable or standard construction and may be wheel mounted in the well known manner, supporting any usual beet 70 harvesting mechanism employed in harvesters of this type.

A supporting rod 5^a is supported by brackets 6 secured to the lower side bar 5 and to one of the front uprights 2. This 80 rod is provided at one end with a strap bearing member 7 which co-operates with a supporting bracket 8 secured to uprights 4 to rotatably support a drive shaft 9 disposed longitudinally of the frame. This shaft is 85 provided on its upper end with a bevel-gear 10 secured thereon adapted to mesh with a drive gear which may be operatively connected to the operating mechanism of the harvester so as to be rotated thereby. In 90 this manner, the drive shaft may be rotated during advancement of the machine by means of the operating mechanism for the harvesting devices or, if preferred, independent means of suitable type may be provided for rotating this shaft.

A disk 11 is secured on the forward end of shaft 9 for rotation therewith. This disk is eccentrically connected by a pitman rod 12 to one end of a connecting rod 13 which 100 is provided adjacent one end with a transverse slot which receives the turned over portion 14 of rod 13, the rod being turned over as shown to provide a sleeve and an offset strap portion which is riveted to the 105 body of the rod. The pitman rod will thus act to reciprocate the connecting rod 13 when the drive shaft 9 is rotated.

Connecting rod 13 is pivotally secured adjacent each end, as at 15, to the rearward end 110

of an operating arm 16 which is pivotally secured intermediate its ends by means of a countersunk pivot pin 17 upon the under face of a supporting plate 18. Suitable 5 guide straps 19 straddle the rearward portions of the operating arms so as to support and guide the same during rocking movement thereof when the connecting rod 13 is reciprocated.

- 10 Each of the supporting plates 18 is provided at its upper end with a sleeve member 20 secured thereon and fitting snugly about the shaft or rod 5^a. These sleeves are secured in adjustment on the rod longitudinally thereof by means of collars 21 positioned at each end of the sleeves and secured in adjustment on the rod by set screws. As will be noted from Fig. 1, when the attachment is in operative position, the supporting 15 plates 18 are at a downward and forward inclination, these plates being freely rockable at their upper ends upon the rod 5^a. The plates may thus be readily rocked toward and away from the ground surface 20 and secured in raised or inoperative position, when desired, or if preferred any suitable means of well known construction may be employed for raising and lowering these plates.
- 25 Each of the plates 18 is provided adjacent its lower end, and at each side thereof, with a substantially rectangular or L-shaped bracket 22 which is secured to the upper surface of the plate and disposed at a slight 30 upward and forward inclination thereto. A substantially U-shaped member 23 is secured to the plate adjacent each side thereof and directly below the bracket 22, this member being disposed in substantial parallelism 35 with the bracket and having its forward arm positioned closely adjacent the forward arm of the same. The brackets 22 and the U-members 23 provide guide frames for guiding a cutting head 24 secured on the forward end of the rockable arm 16, this head being disposed at a slight forward and upward inclination to the arm and being provided, at its forward edge, with a plurality of contiguous cutting teeth 40 45 which are beveled downwardly to form cutting edges. During advancement of the machine, the cutting heads 24 are reciprocated at relatively high speed, these heads serving to cut or sever the tops from the 50 55 beets with which they are brought into engagement.

60 A guide plate 26 is mounted in advance of the lower end of each of the supporting plates 18. This guide plate is of arcuate shape being arched upwardly and forwardly of the plates 18, and is provided at each side with an integral substantially rectangular supporting bracket 26^a, the rearward end bar of which is detachably secured by securing screws 27 to the forward end bars of

the brackets 22 and the members 23. As will be noted, the lower bars 28 of the brackets 26^a form substantial continuations of the lower bars 29 of the brackets or U-members 23.

70 In practice, the supporting plates 18 are adjusted on the supporting rod 5^a so that, when the harvesting machine is advanced along the rows of beets, one of these plates will be positioned above each row, the guide 75 plates 26 traveling a short distance above the ground surface, and the lower bars 29 of the U-members 23 constituting runners for supporting the lower ends of the supporting plates. As the guide plate 26 is advanced along the row, it engages the leaves or tops of the beets so as to bend them over to expose the crown of the beet, the top being then severed from the body of the beet by the action of the cutting head. Also, the 80 guide plates act to support the cutting head in predetermined relation to the root or body of the beet during the cutting operation so as to insure that this operation will be accurately performed, thus avoiding wastage 85 due to cutting an unnecessary amount from the top of the beet root.

90 It will be evident that there may be slight changes made in the construction and arrangement of the details of our invention 95 without departing from the field and scope of the same, and we intend to include all such variations as fall within the scope of the appended claims, in this application in which a preferred form only of our invention 100 is disclosed.

What we claim is:

1. The combination with a beet harvesting machine including a supporting frame, of a supporting plate hingedly secured to 105 said frame for rocking movement about a horizontal axis and projecting downwardly and forwardly therefrom, a cutting head mounted on said plate at the lower arm thereof for reciprocation transversely thereof, and means for engaging the ground surface so as to support the lower end of said supporting frame above the ground, said means also constituting means for guiding the cutting head during reciprocation 110 thereof.

115 2. In an attachment for beet harvesters, a supporting rod adapted to be secured in a beet harvester frame transversely thereof, a supporting plate hingedly secured at 120 one end to said rod so as to be freely rockable about the same, said plate projecting downwardly and forwardly from the rod, an operating arm rockably mounted upon said plate intermediate the ends thereof, a 125 cutting head secured on the forward end of said arm and projecting beyond the lower end of the supporting plate, means for rocking said arm so as to reciprocate the head transversely of the supporting plate, and 130

means for guiding said head during reciprocation thereof adapted to slidably support the lower end of the plate upon the ground surface and to maintain said supporting plate in spaced relation to the ground.

3. In an attachment for beet harvesters, a supporting rod adapted to be secured in a beet harvester frame transversely thereof, a supporting plate hingedly secured at its upper end to said rod, an operating arm extending longitudinally of said supporting plate and pivotally secured thereto intermediate its ends, a cutting head carried by said arm at the lower end thereof and projecting beyond the lower end of the supporting plate, means for engaging the ground surface so as to slidably support the lower end of said supporting plate above the ground, said means being adapted to guide the cutting head during reciprocation thereof, an operating shaft rotatably supported at one end of said supporting rod, a disk secured on said shaft, and a pitman eccentrically connected to the disk and secured to said arm so as to cause rocking movement thereof for reciprocating the cutting head when said arm is rocked.
4. In an attachment for beet harvesters, a supporting rod adapted to be secured in a beet harvester frame transversely thereof, two parallel supporting plates hingedly secured to said rod at their upper ends for free rocking movement about the rod, means for adjusting said supporting plates toward and away from each other longitudinally of the rod so as to position the same above the rows of beets along which the harvester is drawn, cutting members carried by the supporting plates at the lower ends thereof, and guide members projecting beyond the plates and adapted to bend over the leaves of the beets so as to expose the crowns thereof, said guide members being disposed in predetermined relation to the cutting members and adapted to support the same in predetermined relation to the root of the beet during the topping operation so as to insure that the proper amount of the beet top will be severed therefrom.

5. In an attachment for beet harvesters, a supporting member, a supporting arm hingedly secured thereto for rocking move-

ment about a horizontal axis, at its upper end, substantially U-shaped members secured to said supporting plate adjacent the lower ends thereof and projecting below and in advance of the same, the lower bars of said members constituting runners for supporting the lower end of the supporting plate during advancement of the same, a cutting head positioned at the lower end of said supporting plate and projecting beyond the same, said head being mounted for movement transversely of the plate and the U-members constituting guides for reciprocation of the head, and means for reciprocating said head.

6. In an attachment for beet harvesting machines, a supporting plate adapted to be secured at one end to a beet harvester frame for rocking movement about a horizontal axis, substantially L-shaped brackets secured to the plate at the other end and adjacent each side thereof, said brackets projecting beyond said plate and at an angle thereto, substantially U-shaped members secured to the plates beneath said brackets and projecting downwardly from the plate, said U-members coöperating with the brackets to form bracing and guide frames, a cutting head slidably mounted in said guide frame for reciprocation transversely of the supporting plate, means for reciprocating said head, and upwardly and forwardly curved guide plates secured to the forward ends of said brackets and U-members and projecting beyond the cutting head at an upward inclination to the plate, said members being adapted to act as guide members for depressing the stems of the leaves of beets so as to expose the crowns thereof and for maintaining the cutting head in predetermined relation to the root of the beet during the topping operation, the lower bars of said U-members constituting runners for supporting the lower end of the plate above the ground surface during advance of said plate.

In testimony whereof we affix our signatures in presence of two witnesses.

CHARLES L. LEONARD.
ALLEN F. HOWARD.
